UNITED STATES PATENT OFFICE.

CHARLES A. MAXFIELD, OF NEW YORK, N. Y., ASSIGNOR TO JACOB WALLEACE, TRUSTEE, OF SAME PLACE.

METHOD OF SATURATING OR COATING TEXTILE FABRICS, PAPER, &c.

SPECIFICATION forming part of Letters Patent No. 328,957, dated October 27, 1885.

Application filed May 23, 1885. Serial No. 166,497. (No model.)

To all whom it may concern:

Be it known that I, CHARLES A. MAXFIELD, a citizen of the United States, and a resident of New York, in the county of New York and State of New York, have invented certain new and useful Methods of Saturating or Coating Textile Fabrics, Paper, &c., of which the following is a specification.

My present invention relates to an improvement in the art of coating textile fabrics, paper, leather, and similar substances with any desirable waterproofing, coloring, or glossing material. In practicing this method the natural wax known as "ozocerite" may be employed; or I make use of paraffine, gums, india-rubber, and analogous strengthening, preserving, and waterproofing substances.

In applying wax and other substances to paper and the like it is usual to draw the material operated upon through a bath of the liquefied waterproofing or other substance, or to apply the said substance to the material to be treated by revolving rolls, which dip into a bath of liquefied substance, and over or under which rolls the material operated upon is arranged to travel.

My object is to introduce a new mode of practicing the art in question, whereby I am enabled to either coat the material operated upon or completely saturate it.

In carrying out my method I by preference make use of an apparatus for which an application for patent has been filed in the United States Patent Office of even date with this, and which apparatus is illustrated in the accompanying drawings, in which—

Figure 1 is a plan view, and Fig. 2 a vertical central longitudinal section.

My method is carried out by depositing a body of wax or other substance directly upon the surface of the paper or other material operated upon within a confined space and drawing the paper beneath said body of wax at variable speeds, according as to whether the paper is to be coated merely or completely saturated, the temperature of the body of wax being regulated according to the character of the result to be produced.

The following is a description of the appa-

ratus, which the accompanying drawings illustrate, and the manner in which it is to be operated in practicing my method.

A indicates a frame, which may be of cast-iron or of any other suitable material. Mounted upon one end of this frame, which is constructed of dimensions adapted for the purpose in view, is the paper-delivery reel B, and at the opposite end of the machine is located the paper-receiving reel C. Both of these reels are provided with shafts B' and C' respectively, which have bearings in the frame of the machine in the usual manner. The upper longitudinal bars, a, of the frame A support the castings, which constitute the receptacle and the distributor.

The receptacle, as shown, is composed of two iron castings, D D', forming the front and rear walls, and that wall D of said receptacle nearer the delivery-reel is so shaped on its under side as to provide a smooth surface for the paper to travel under and insure close contact between paper and casting while the paper is passing under the receptacle, as shown. The inner surface of the casting D is vertical and smooth, except near its lower end, where it is provided with a projection constructed to form one element of a dovetail connection. A pipe, d, is located within this casting D, as shown, and at the top of said casting is a flat piece of metal, d', of the requisite length secured rigidly thereto and provided with screw-bolts, whereby the said casting D may be adjusted longitudinally of the frame in order to increase or diminish the distance between the castings D and D'. The casting D' is similarly constructed, except that it has no projection on its inner face, as is the case with the casting D. It is preferably curved on its outer surface and flat on its under surface, and it has secured to its inner wall, by set-screws e, the blade E, or this blade may be cast as part of it. The holes to receive these set-screws e are elongated, in order to permit the blade to be adjusted vertically, so as to enable said blade to be accurately placed in position upon the casting. On the lower face of the blade E is a projection forming one element of a dovetail joint. The blade E may project

upward above the frame of the machine. The casting D' is also provided with a pipe, d, and with the flat piece of metal d² at its top having set-screws, which permit the adjustment of 5 said casting lengthwise of the machine, in order to bring it nearer to or farther from the casting D.

F represents the two-part side plates. These plates overlap each other, and are adjustable in length by means of the set-screw f. The outer end of each of these plates is provided with a slot formed so as to receive the projection on the inner wall of the casting D and blade E, respectively, thereby completing 15 the dovetail joint between the respective castings and the side plates. There are two sets of the plates F, one at each end of the receptacle, and they are of sufficient height to form the end walls of said receptacle, and while 20 their upper edges are straight their lower edges incline slightly from the casting D to the beveled edge of the blade E, so as to insure an easy movement of the paper beneath the receptacle.

25 The blade E, forming the rear wall, may be made without the casting D', and heated in another manner.

Immediately above the receptacle is a tank, G, which is supplied with the coating or saturating material, liquefied and kept hot by any suitable means. At the bottom of this tank is a series of discharge-cocks, g, having projections from their plugs connecting with a rod, g', whereby all the cocks may be opened 30 at the same time and in the same degree, and thus insure the supply of the liquid to the receptacle evenly over the surface of so much of the material operated upon as for the moment forms the bottom of this receptacle.

40 From this description it is plain that my receptacle has no bottom; that its front and rear walls are formed by the castings D and D' E, which may be adjusted toward or from each other, so as to increase or decrease the space between said walls; that its side walls are formed by the two sets of side plates, F, which are detachably connected to the castings D D' E, and which may be adjusted in length by the set-screws, so as to accommodate themselves 45 to the adjustments of the castings D D' E. The side plates are also adapted to be moved transverse of the machine toward or from each other, in order to increase or diminish the width of the receptacle according to the width 50 of the paper or fabric operated upon. The longitudinal adjustment of the receptacle is for the purpose of increasing or diminishing the surface of the liquefied substance in contact with the material operated upon.

55 Projecting from the edges of the plates F are lugs f', which receive set-screws f², so that when the plates F are properly adjusted they may be locked in position.

H represents a pivoted bar secured upon the 60 frame of the machine by a central pivot and extending transverse of the frame. This bar

is located just in advance of the delivery-reel B, and is adapted to hold the paper above the lower surface of the casting D, so as to insure proper contact between the paper and the 70 lower surface of said casting. The fact that the bar H is pivoted also insures the passage of the paper beneath the receptacle in an unruffled manner, as any irregularities in the paper are compensated for by the automatic 75 adjustment of said bar.

At a suitable position on the frame is secured the casting I, which is constructed the same as casting D', having an interior pipe, d, and flat and curved walls. To the flat face of 80 this casting is secured in a detachable and adjustable manner the blade J, whose lower end is beveled. The casting I is adjustable longitudinally of the machine by the set-screws passing through the plate at its top. The 85 function of plate J is to further insure the even distribution of the material upon the paper or fabric operated upon.

Between the castings D' and I is arranged the bar K, pivoted to the frame and capable of 90 being thrown in and out of the operation when desired. The function of this bar K is to keep the paper properly in contact with the blades E and J.

The tension on the delivery-reel B is regulated by the device shown as a part of Fig. 2. The application of this device to the shaft of the delivery-reel is shown in Fig. 1. This tension device consists of a metal strap, K', secured at l and passed over the shaft B', the 95 free end of the strap being connected to the spring m, which spring is connected with a bar, n, the latter being secured near the base of the machine and provided with means for depressing or elevating it, so as to increase or decrease the strain on the spring, and thereby 100 easily regulate the tension of the delivery-reel.

The pipes d, forming parts of the castings D, D', and I, are connected by means of suitable couplings with steam-supply pipes L.

Hot air or hot water may be used instead of steam for heating the castings forming the receptacle and the casting I, and for convenience the pipe of casting D' may be connected permanently with the pipe of casting I, in which case the longitudinal adjustment of these two castings will not be independent of each other, and the relative distance between the castings of the receptacle will be regulated by the longitudinal adjustment of the casting D.

In operation the paper or other material to be treated is conducted from the delivery-reel B over the pivoted bar H, under the bottom of the casting D, and beneath the open bottom of the receptacle and blade E, from which point it is carried over the pivoted bar K, under the blade J of casting I to the receiving-reel C. In this position the paper or material to be operated upon forms the bottom of 120 the said receptacle. The parts being adjusted as contemplated the liquefied material, when 125

permitted, will flow from tank G through the stop-cocks g upon the paper or fabric forming the bottom of the receptacle D D' E. The depth of the liquefied substance resting upon 5 the paper or other material operated upon is of course to be regulated according to the quality of paper or other material operated upon, and according as to whether the paper is to be saturated or merely coated. In operating with 10 very thin paper but a small depth of liquid—say about a half to three-quarters of an inch—would be allowed to pass into the receptacle, and this would be the practice in operating upon heavy paper where the object is to coat 15 and not saturate. If the liquid is to be struck through the paper, so as to saturate it, a heavier body of liquid—say about two to three inches—would be allowed to enter the receptacle D D' E. The liquid in the receptacle 20 D D' E is kept at a predetermined temperature by regulating the degree of heat permitted to affect the castings forming the walls of said receptacle.

The revolution of the reel C draws the paper 25 M from the reel B over the equalizing pivoted tension-bar H, under the wax-receptacle and under the blade J, after passing which latter point it is sufficiently treated to be wound upon the receiving-reel C.

30 The blade E prevents any undue quantity of the liquefied material from adhering to the paper or other material being treated, and such as remains upon the paper or other material treated is further equalized upon its 35 surface during the act of passing under the blade J.

In practice I may dispense with the front wall, D, of the receptacle, leaving this receptacle to be formed of the rear wall, D' E, and 40 attached side walls, F, with the incline of the material operated upon, the walls F being made with an incline to conform.

It will be noticed that the substance to be applied to the paper or other fabric is not fed 45 from a hopper upon said paper or fabric, but is deposited in a body directly thereupon. The temperature of the substance is easily regulated by regulating the heating medium whereby the said substance is kept hot. If 50 the material operated upon is to be coated, merely, a comparatively low degree of heat is to be applied to the wax or other substance; but if the material operated upon is to be saturated the wax or other substance will be 55 made quite hot.

The paper or other material operated upon will also be drawn rapidly or slowly beneath the confined body of liquefied substance, according as to whether the material operated upon is to be merely coated or saturated, as 60 in coating a quite rapid movement of the material operated upon will be necessary, while in saturating the movement of said material will be slower. This operation is controlled by regulating the receiving-reel. 65

The leading characteristic of my method is the depositing of a body or mass of the liquefied substance in a confined space, directly upon the surface of the material operated upon, and the drawing of said material beneath or away from said confined mass of liquefied substance, the degree of penetration of the liquefied substance into the material operated upon depending, primarily, upon the depth of the mass of said liquefied 75 substance in contact with the material operated upon. 70

Having thus described my invention, what I claim as new, and desire to secure by Letters Patent, is— 80

1. In the art of coating or saturating textile fabrics, paper, leather, and similar materials with any desirable waterproofing, coloring, or glossing substance, the method of applying said substance, which consists in depositing 85 a liquefied body or mass of the same in a confined space directly upon the surface of the material operated upon, and drawing said material beneath or away from said confined mass of liquefied substance, substantially as 90 set forth.

2. In the art of coating or saturating textile fabrics, paper, &c., with any waterproofing, coloring, or glossing substance, the method of applying said substance and regulating the 95 degree of penetration thereof into the material operated upon, which consists in depositing a liquefied body or mass of the substance of predetermined depth, in a confined space, directly upon the surface of the material operated upon, and drawing said material beneath or away from said confined mass of liquefied substance, substantially as set forth. 100

Signed at New York, in the county of New York and State of New York, this 19th day 105 of May, A. D. 1885.

CHARLES A. MAXFIELD.
